(Cl. D47—7)

To all whom it may concern:

Be it known that I, Abrasha Wilcher, a citizen of the United States, residing at Manchester, New Hampshire, have invented a new, original, and ornamental Design for a Lady's Stocking, of which the following is a specification, reference being had to the accompanying drawing, forming a part thereof, in which:

Figure 1 is a fragmentary perspective view of a lady's stocking as seen from the rear of the stocking and looking at the heel section and sole.

Figure 2 is a perspective view looking at the side of the stocking.

The shading indicates a slightly heavier reinforced heel section in contrast with the other portions of the stocking.

I claim:

The ornamental design for a lady's stocking, as shown and described.

ABRASHA WILCHER.
